United States Patent Office.

EVERETT CLEMONS, OF CATAWISSA, PENNSYLVANIA.

Letters Patent No. 106,255, dated August 9, 1870.

IMPROVEMENT IN SEAL-LOCKS.

The Schedule referred to in these Letters Patent and making part of the same

To all whom it may concern:

Be it known that I, EVERETT CLEMONS, of Catawissa, in the county of Columbia, and in the State of Pennsylvania, have invented certain new and useful Improvements in Locks; and do hereby declare that the following is a full, clear, and exact description thereof, reference being had to the accompanying drawing and to the letters of reference marked thereon, making a part of this specification.

The nature of my invention consists in the construction and arrangement of a "lock," as will be hereinafter fully set forth.

In order to enable others skilled in the art to which my invention appertains to make and use the same, I will now proceed to describe its construction and operation, referring to the annexed drawing, in which—

Figure 1 is a longitudinal vertical section of my lock;

Figure 2 is a view of the rear end;

Figure 3, a plan view, and

Figure 4, a view of the front end of the same;

Figure 5 is a cross-section of the lock, through line *x y*, fig. 1; and

Figure 6 is a side view of the key.

A represents the lock-casing, which is of cylindrical form, and on one side of which, between two ears, is pivoted the hasp *B*.

The end of the hasp *B* enters the casing *A*, and is provided with a recess, into which closes the bolt *C*, forced by a spiral spring, *D*, which retains the bolt in place.

In the back end of the casing *A* is a beveled or dovetailed recess, *E*, to admit of a metallic disk or seal, which, when properly compressed, is securely held in the end of the lock, and prevents the movement of the bolt by closing the aperture through which the end *a* of the bolt *C* works.

Near the back end of the lock is formed a shoulder, *b*, on which to secure a press or device for crushing the metallic seal or disk into the recess *E*, and stamping it with such device or letters as may be desired.

From the outside rim of the lock to the bottom of the beveled recess *E* is cut a slot or opening, *d*, to admit of a suitable instrument for removing the seal.

The bolt *C* is provided with an extension or bent bar *G*, which passes forward into a hole in a plate, *H*, inserted in the case *A* a suitable distance from the front end.

In the center of this plate is the key-hole pin *a*.

The hole into which the bar *G* enters on the plate *H*, is, on the front side of said plate, covered by a spring, *I*, fastened at *f*, as shown in fig. 5, said spring being forced back from the opening by turning the key round to the stop *g*, which prevents the key from being turned beyond the opening.

Now, the bolt *C* can be released from the catch in the hasp *B* by pressing forward upon the key.

h is a guard, or series of wards, to which the key is fitted.

Having thus fully described my invention,

What I claim as new, and desire to secure by Letters Patent, is—

The combination of the casing *A* with beveled recess *E*, bolt *C*, with bent extension *G*, spring *D*, and hasp *B*, all constructed and operated substantially as set forth.

In testimony that I claim the foregoing, I have hereunto set my hand this 4th day of May, 1870.

EVERETT CLEMONS.
